Primary Examiner — Richard E Chilcot

(57) **CLAIM**

The ornamental design for a safety belt for the seats of vehicles, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1.1 is a perspective view of a safety belt for the seats of vehicles;

FIG. 1.2 is a right side elevational view thereof;

FIG. 1.3 is a top plan view thereof;

FIG. 1.4 is a front elevational view thereof;

FIG. 1.5 is a left side elevational view thereof; and

FIG. 1.6 is an enlarged partial view of the right side elevational view thereof.
